(57) **CLAIM**

The ornamental design for a mobile phone, as shown and described.

DESCRIPTION

FIG. 1 is a rear perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view thereof;

FIG. 9 is a rear view thereof showing the state in which the relevant icons have been emerged on the small LCD display below the rear camera part in order for the user to easily check if they receive a text message, etc.; and,

FIG. 10 is a rear perspective view thereof showing the state that the small LCD display below the rear camera part disappears when the mobile phone is turned off.

The broken lines are for illustrative purposes only and form no part of the claimed design.

The Facebook mark or trademark in FIG. 9 forming part of the claimed design is a registered trademark of Facebook, Inc. The Twitter mark or trademark shown in FIG. 9 forming part of the claimed design is a registered trademark of Twitter, Inc. Trademarks are the property of their respective owners.

1 Claim, 9 Drawing Sheets
